EXTRACTION AND DEWAXING OF
LUBRICATING OILSFrancis X. Govers, Vincennes, Ind., assignor to
Indian Refining Company, Lawrenceville, Ill.,
a corporation of MaineNo Drawing. Application April 20, 1931
Serial No. 531,597

4 Claims. (Cl. 196—17)

This invention relates to a process for the manufacture of lubricating oils, and more particularly to a process for the treatment of wax-bearing hydrocarbon oils to effect removal of their 5 wax constituents, whereby lubricating oils substantially free from wax are obtained.

In a prior application, Serial No. 313,346, filed October 18, 1928, now Patent 1,802,942 and entitled, Process for recovery and purification of lubricating oils from mineral oils, I have described 10 a method for the manufacture of low cold test oil by the removal of solid hydrocarbons from wax distillate. The present invention, which is a continuation in part thereof, relates to the treatment 15 of wax-bearing lubricating oil fractions wherein the removal of the solid hydrocarbons or wax constituents is carried out in two or more steps.

The invention broadly contemplates the preparation of low cold test lubricating oil fractions 20 from wax-bearing hydrocarbon oils, such as wax distillate or the like, by a process wherein the oil, which may have been subjected to any desired preliminary refining treatment, is dissolved in a solvent possessing the properties of dissolving all hydrocarbons contained therein at elevated temperatures and having a selective 25 solvent action between the liquid hydrocarbons and solid hydrocarbons at relatively low temperatures. The resulting solution is then chilled to effect precipitation of the solid hydrocarbons, and the mother liquor of solvent and dissolved liquid hydrocarbons is removed from the precipitated material by filtration, following which the mass 30 of separated solid hydrocarbons and liquid associated therewith is commingled with fresh solvent oil and while maintained in a cooled condition again subjected to filtration to remove the solvent and dissolved oil from the remaining 35 solid hydrocarbons.

In the prior application, Serial No. 313,346, above referred to, I have described subjecting the wax-bearing lubricating oil to a single dewaxing step wherein the wax-bearing oil is dissolved in a suitable solvent liquid which, at temperatures of approximately 100° F., has substantially complete solvent action on a mineral oil wax distillate substantially free from constituents having a boiling point equal to or below that of 45 gas oil, and at temperatures of —5° F. and below has substantially complete solvent action on the liquid hydrocarbons therein but substantially no solvent action on the solid hydrocarbons therein and of such a nature that upon cooling a solution 50 of such mineral oil wax distillate in the solvent

liquid to 0° F. and removing the solid hydrocarbons so precipitated and the solvent liquid the resulting oil has a cold test of substantially 0° F. The resulting solution is then chilled to a temperature at which substantially all of the solid 60 hydrocarbons separate, whereupon the chilled mixture is subjected to filtration to remove the solvent and dissolved liquid hydrocarbons, depositing the solid hydrocarbons in the form of a filter cake of slack wax. 65

The resulting cake of slack wax comprises a substantial portion of solvent and liquid hydrocarbons retained within the crystalline mass of wax and which retained oil is not only valuable as a lubricant, but also its presence in the wax 70 cake renders the latter unsatisfactory for sweating. I have discovered that this retained oil adhering in the slack wax is particularly valuable as a lubricating oil for internal combustion engines and the like. It is of a more distinctive 75 paraffinic nature and tends to possess a very flat temperature viscosity relationship combined with low specific gravity. An important characteristic of this oil is its relatively narrow increase in viscosity between 100° F. and 210° F. as well as 80 between intermediate points of temperature as compared with lubricating oils of the prior art and also as compared with the liquid fractions removed in the initial filtration and which characteristic is essential in the preparation of a superior type of lubricant adapted for the lubrication 85 of internal combustion engines.

It is an object of my invention, therefore, to carry out the dewaxing process in successive stages wherein, during the first stage, all of the 90 solid hydrocarbons may be removed as a wax concentrate or slack wax, and during a succeeding stage the resulting wax concentrate is mixed with additional solvent and subjected to refiltration while in a cooled condition to effect more complete separation between 95 oil and wax constituents. During the first stage the wax-bearing oil is dissolved in a solvent possessing the property of dissolving all the hydrocarbons at an elevated temperature of say 90° 100 F. and above, and having a selective action between the liquid hydrocarbons and solid hydrocarbons at lower temperatures. The solution is then cooled to a relatively low temperature, as for example, 0° F. or below to effect separation 105 of the solid hydrocarbons, whereupon the cooled mixture is introduced to filtering means to remove the solvent liquid and dissolved liquid hydrocarbons and form a filter cake of slack wax composed of solid and semi-solid hydrocarbons 110

together with adhering solvent and dissolved liquid hydrocarbons.

During the next stage, the above filter cake is removed and advantageously commingled with 5 fresh cooled solvent. While substantially the same or even lower temperature conditions may be maintained during this second step, it may be of advantage, however, to employ slightly higher temperatures so as not only to effect complete solution of the adhering liquid but also to dissolve those particularly desirable oil constituents which, as already mentioned, may exist in close association with the solid hydrocarbons separated during the initial dewaxing step and are removed 10 as a component part of the slack wax. By properly selecting the temperature conditions under which to carry out each of the filtration steps, I am able to obtain lubricating oils possessing different characteristics of gravity, viscosity and 15 pour test as may be desired. The commingled mixture, which may undergo further chilling if desired, is then subjected to further filtration to remove the solvent and dissolved oil and form a filter cake of solid hydrocarbons. The resulting 20 reformed filter cake may be freed of its associated or adhering liquid by washing, in situ, with fresh solvent to thereby produce a wax cake which, after removal by evaporation of the remaining solvent retained therein, is in a suitable 25 condition for sweating or for disposition, as 30 may otherwise be desired.

Furthermore, I have found that by regulating the temperature during the washing of the reformed slack wax cake, that is, by washing, for 35 example, in one or more steps while maintaining suitably different temperature conditions in each step, I may effect a selective washing of the slack wax whereby the oil originally retained therein or associated therewith is removed in selective 40 fractions, having gravity viscosity relationships of the particular degree desired.

As an example in the practice of my invention, I dissolve 1,000 gallons of wax distillate having a viscosity of 450 Saybolt universal seconds at 45 100° F. in 3,500 gallons of a mixture of solvent, consisting of approximately 37% acetone and 63% benzol, and cool the solution to -10° F. to effect precipitation of the solid hydrocarbons. The cooled mixture of dissolved oil and solid matter suspended therein is introduced to a filter 50 press, advantageously of the rotating leaf type, wherein the solvent and dissolved liquid hydrocarbons are removed and a filter cake of slack wax of desired thickness is formed on the filter leaves, after which filtration is stopped and the liquid content blown back or displaced with gas which latter also serves to displace liquid from the filter cake and so dry it. The resulting filter 55 cake comprising approximately 740 gallons of slack wax, of which approximately 280 gallons represents solid and retained liquid hydrocarbons, is removed from the press and transferred to a tank or other suitable container, provided with stirring apparatus, wherein the slack wax is thoroughly 60 commingled with 1,110 gallons of solvent similar to that used in the initial filtering operation, the temperature of the mixture being maintained or regulated by passage through suitable cooling coils.

70 The resulting mixture of oil at a temperature of 0° F. or below is then pumped into a second filter to separate the solvent and dissolved liquid hydrocarbons from the solid hydrocarbons. When a cake of desired thickness is obtained, 75 the liquid contents of the still may be displaced

by blowing with gas, as explained above, and the reformed cake of solid hydrocarbons is then washed by passing approximately 2,400 gallons of cold solvent liquid through the cake, in order to remove entrained liquid and produce a substantially oil-free sweatable cake. 80

Depending on the character of the wax-bearing oil undergoing treatment, the initial wax cake may be of such a nature that the adhering or retained liquids contained therein may be separated without the addition thereto of appreciable amounts of additional solvent liquid, and by subjecting the slack wax which already has substantial amounts of solvent associated with it, to a pulping action by stirring or agitation so as to disrupt the structure of its crystal mass whereby the separation of the occluded liquid is facilitated. The disrupting action obtained by subjecting the cake to such stirring or agitation facilitates separation of liquid occluded or retained in the mass of crystalline wax, thereby permitting its more ready removal from the solid hydrocarbons during the subsequent filtering step or effecting its subsequent removal during washing of the resulting filter cake with a 90 minimum of solvent wash liquid. 95

One of the most necessary qualities in a sweatable wax is that of uniformity; not only must it have the right crystalline structure with not over a definite percentage of sweatable oil, but in addition its retained oil must be uniformly distributed throughout rather than segregated into spots since such segregation of the oil in spots tends to bring about solution of wax in the oil in such spots rather than permitting uniform sweating 105 of the oil from the crystals. This segregation is the result of non-uniform size and distribution of the crystals formed during precipitation of the wax from the solvent used, and these non-uniform crystals tend to distribute themselves 110 evenly on the filtering surface and thus, whether pressure is applied in order to get a fairly dry cake, or the cake is washed with solvent in order to wash out entrained liquid, this unevenness of size and distribution of crystals frequently 115 results in wax cakes that are not sweatable. I have found that by subjecting the cake to mechanical working the crystal structure of its mass can be readily changed into a form that is easily filter pressable or easily washed in a filter press 120 of the rotating leaf type. This change in structure is readily accomplished by removing the cake from the original filter means and agitating or stirring it in order to produce uniformity of crystal size and facilitate even distribution of its 125 constituent parts on refiltration. This uniform 130 sizing of the crystals is advantageously performed in the presence of added chilled solvent liquid.

The filtrate produced in the initial filtration stage will contain approximately 72% of the total 135 available amount of pressed distillate or filtered oil, and such oil, after removal of the solvent, will have a cold test of approximately -5° F. The filtrate produced from the filtration of the commingled slack wax and solvent liquid, which 140 will contain a substantial amount of oil of a desired pour point, may be mixed with the filtrate resulting from the initial filtration step, although as I have already set forth, this oil may be disposed of to better advantage in a different manner and for different purposes, since it possesses certain desirable viscosity characteristics. 145

The washed cake is removed to a still where the solvent is evaporated off and recovered and the wax with the solvent removed is run to sweat 150

pans and sweated in the usual manner to the desired melting point. The recovered solvent, together with all or a portion of that recovered from the washing of the cake while in the filter, 5 may be used in dissolving fresh charge to the system. The last portions of wash solvent passing through the cake will contain very small amounts of dissolved oil and may, therefore, be used for dissolving either fresh charge or slack wax without first removing its dissolved oil content.

While the example described sets forth one mode of operation, the invention is not restricted to any particular set of operating conditions, such 15 as those of temperatures, etc., and I may find it of advantage to employ different temperatures, or vary the temperatures maintained during succeeding steps of the operation for the purpose of obtaining products possessing different characteristics as may be desired.

Obviously many modifications and variations 20 of the invention, as hereinbefore set forth, may be made without departing from the spirit and scope thereof, and therefore only such limitations should be imposed as are indicated in the appended claims.

I claim:

1. The process of manufacturing low cold test lubricating oil which comprises mixing a wax-bearing mineral oil with acetone and benzol in such a ratio to each other and to the said mineral oil that the acetone and benzol together at temperatures of approximately 100° F. have substantially complete solvent action on such wax-bearing mineral oil and at temperatures of -5° F. and below, have substantially complete solvent action on the liquid hydrocarbons therein but substantially no solvent action on the solid hydrocarbons therein and upon removal of solid hydrocarbons and the acetone and benzol such mineral oil has a cold test of substantially the same as the temperature of the mixture at the time of the removal of the solid hydrocarbons, cooling the mixture to a temperature at which a concentrate comprising wax and hydrocarbons of relatively flat viscosity-temperature relationship is formed, filtering from the mixture the mother liquor of solvent liquid and dissolved oil, mixing the resulting concentrate with additional cool solvent, introducing the mixture to filtering means, filtering from the mixture the solvent liquid and dissolved oil, and removing adhering and entrained liquid hydrocarbons from the cake by washing the cake, in situ, with solvent liquid.

2. The process of manufacturing low cold test

lubricating oils of desired viscosity-temperature relationship by dewaxing wax-bearing mineral oil in stages comprising dissolving the wax-bearing oil in a selective solvent comprising acetone and benzol mixed in substantial proportions, cooling the solution to a temperature of 0° F. or below to form a semi-solid concentrate of wax and hydrocarbons of relatively flat viscosity-temperature relationship, separating the concentrate from the cold mixture, mixing the concentrate with fresh solvent acetone and benzol liquid mixture to dissolve the oily constituents of desirable viscosity-temperature characteristic, and filtering the cool mixture to separate the wax therefrom.

3. The process of manufacturing low cold test lubricating oils of desired viscosity-temperature relationship by dewaxing wax-bearing mineral oil in stages comprising dissolving the wax-bearing oil in a selective solvent comprising acetone and benzol mixed in substantial proportions, cooling the solution to a temperature of 0° F. or below to form a concentrate composed of solid wax and semi-solid hydrocarbons together with adhering solvent and dissolved liquid hydrocarbons, separating the concentrate from the cold mixture, mixing the concentrate with fresh solvent liquid to dissolve the oily constituents characterized by a flat viscosity-temperature relationship, filtering the mixture at a temperature of around 10° F. or below to remove the solvent 100 and dissolved oil and form a filter cake of slack wax, and washing the resulting cake with fresh solvent liquid at a temperature slightly above the filtering temperature in order to substantially completely remove adhering oil from the wax 110 cake.

4. The process of manufacturing low cold test lubricating oils of desired viscosity-temperature relationship comprising dissolving the wax-bearing oil in a selective solvent comprising acetone 115 and benzol mixed in substantial proportions, cooling the solution to a temperature of 0° F. or below to form a concentrate composed of solid wax and semi-solid hydrocarbons, together with adhering solvent and dissolved liquid hydrocarbons, separating the resulting concentrate from the cold mixture, and washing the concentrate in stages with fresh solvent acetone and benzol liquid mixture at temperatures successively increasing 120 above that at which the concentrate was separated from the original solution in order to dissolve out fractions of contained oil of desired viscosity-temperature relationship.
